UNITED STATES PATENT OFFICE.

ROSS ALEXANDER WORKMAN, OF TULSA, OKLAHOMA.

WASHING MACHINE.

Application filed May 25, 1921. Serial No. 472,342.

To all whom it may concern:

Be it known that I, Ross A. WORKMAN, a citizen of the United States, residing at Tulsa, in the county of Tulsa and State of Oklahoma, have invented certain new and useful Improvements in Washing Machines; and I do hereby declare the following to be a full, clear, and exact description of the invention, such as will enable others skilled in the art to which it appertains to make and use the same.

The present invention relates to clothes washing machines and aims to provide improvements in a washing machine utilizing an oscillatory or reciprocatory tub, for the efficient and convenient washing of clothes, and other fabrics.

Another object is the provision of novel means for mounting the tub for reciprocatory motion, for the effective agitation of the water in the tub.

A further object is the provision of novel means within the tub for the action of the water and clothes thereover to accomplish the cleaning of the clothes, and such means providing a settling chamber in which the dirty water can settle, to be drained off at intervals.

A further object is the provision of novel means for preventing the water from splashing from the tub during the reciprocation thereof, should the water find its way past the cover or lid, thereby avoiding the spilling or running over of the water on the exterior of the tub.

The invention has for another object the provision of novel actuating means for driving the tub in an efficient manner and for the convenient connection of the tub with and disconnection thereof from the driving means.

With the foregoing and other objects in view, which will be understood as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein:—

Figure 1 is a side elevation of the machine, portions being broken away and shown in section, depicting the tub in intermediate position in full lines and in one extreme position in dotted lines.

Fig. 2 is an end view of the machine, portions being broken away and shown in section.

Fig. 3 is a cross section of the lower portion of the tub taken on the line 3—3 of Fig. 2.

Fig. 4 is an enlarged sectional view of the clutch device taken on the line 4—4 of Fig. 1.

Fig. 5 is a section on the line 5—5 of Fig. 4.

Fig. 6 is a detail view of one of the frame raising and supporting devices showing it in position with the corresponding leg raised.

The machine includes a suitable frame 10 having the legs or posts 11 at the four corners, and supported on rollers or casters 12 in order that the machine can be readily moved about on the floor.

In order to raise the frame and support it with the rollers or casters 12 off the floor, and to prevent the machine from being moved when in one position, a lifting and supporting device is provided for each leg 11, and includes a vertical supporting rod 13 slidable in the guide ears 14 outstanding from the leg 11. The upper end of the rod 13 is pivoted, as at 16, to an ear 17 extending laterally from a lifting lever 18 between the ends of said lever. The lever is bifurcated at one end and provided with a pin 19 on which a roller 19' is rotatable to travel in an inclined slot 20 in the ear 15 extending from the leg 11. A coiled expansion spring 21 surrounds the rod 13 and is confined between the lower ear 14 and a pin 22 secured to the rod 13 under the upper ear 14, whereby said spring has a tendency to raise said rod.

When the free ends of the levers 18 are swung upwardly, as seen in Fig. 2, the rollers 19' move inwardly in the slots 20, and the rods 13 are slid upwardly in the ears 14 by the springs 21 until the pins 22 contact with the upper ears 14. This retracts the rods 13 off the floor, so that the rollers or casters 12 rest on the floor, for the free and easy movement of the frame on the surface on which the machine rests. When it is desired to raise the frame and support it with the rollers 12 off the floor, the levers 18 are swung downwardly, thereby depressing the rods 13 against the floor, and the rollers 19' moving outwardly in the slots 20 will lift the frame 10. The levers 18 swing on the pivots 16 and the rollers 19'

move outwardly past the vertical axes of the rods 13, in order that the weight of the frame in bearing down on the rollers 19', will tend to swing the levers 18 downwardly, 5 thereby retaining the lifting and supporting devices in such position, until the levers are swung upwardly to move the rollers 19' inwardly past the axes of the rods 13, when the weight of the machine will swing such 10 levers inwardly and downwardly at their upper ends, to permit the frame to again come to rest on the rollers 12, the springs 21 raising the rods 13 off the floor. In this way, when it is desired to have the machine 15 stand in its position, without danger of moving about, it is lifted and supported by such devices on the legs.

The tub or casing 23, which is made of sheet metal or other suitable material, is 20 of elliptical contour in side elevation, and its side walls are inclined so as to diverge upwardly, as seen in Fig. 2.

The tub is supported between the opposite sides of the frame 10 for longitudinal reciprocatory or oscillatory motion and in 25 order to support the tub, longitudinal bars 24 are secured to the side walls of the tub at the major diameters thereof. At each 30 side of the tub within the frame 10 is provided a pair of crossing oscillating bars 25 having their upper ends pivoted to the corresponding bar 24, as at 26. The lower ends of the bars 25 are mounted for oscillation on transverse rods 27 secured in the 35 lower portion of the frame 10. These oscillating bars 25 being inclined oppositely and crossing one another will result in a peculiar reciprocating or oscillating motion of the tub longitudinally. Thus, when the 40 tub is moved longitudinally in either direction, the forward end of the tub moves downwardly slightly on arc, while the rear end portion of the tube moves upwardly on an arc, to a position as shown in dotted lines 45 in Fig. 1, owing to the fact that one bar 25 of each pair swings downwardly while the other bar swings upwardly. The pivot points 26 between said bars 25 and the tub thus swing around the parallel axes of the 50 rod 27, producing a motion which is the component of two oscillatory movements, and thereby obtaining an effective reciprocatory motion in which the opposite ends of the tub are alternately raised and lowered 55 with a rocking action and the tub reciprocated longitudinally, although the center of the bottom of the tub has very little longitudinal and vertical motion.

Inclined retractile springs 28 have their 60 upper ends connected to the bars 25 near the upper ends of said bars, and the lower ends of said springs are connected to the corner posts of members of the frame 10, thereby pulling downward and outward on said oscillating bars to make the reciprocating ac-

tion of the tub easier and smoother, as well as balancing the motion of the tub back and forth.

The bottom of the tub 23 is formed intermediate its ends with a transverse trough or depression 29 into which the dirty water settles, and such trough being at the central portion of the bottom, will have very little motion either vertically or longitudinally of the tub. A member 30 of sheet metal or 70 other suitable material is disposed over the trough 29 on the bottom of the tub and has the inclined ends 31 to fit the side walls of the tub, and also has the opposite inclined stepped sides 32 providing wash boards 80 against which the clothes rub to assist in dislodging the dirt therefrom, similar to the rubbing of clothes on an ordinary wash board. The opposite sides of the member 30 being inclined, will also deflect the water 85 upwardly by the relative longitudinal motion of the water and tub during the reciprocation of the tub, thereby resulting in the effective agitation and motion of the water. Plates 33 are secured to the ends 31 of the 90 member 30 within said member and depend therefrom to enter the ends of the trough 29, thereby retaining the member 30 in position, and said plates also preferably serve as weights for holding the member 30 down 95 on the bottom of the tub.

The sides 32 of the member 30 have the lower inclined edge portions 34 provided with longitudinal series of small apertures 35 directly adjacent to the lower edges of 100 said sides, for the flow of dirt-laden water along the bottom of the tub under the sides 32 of the member 30 and into the trough 29. The upper portions 36 of the sides 32, immediately adjacent to the top of said member 30, are also provided with longitudinal 105 series of small apertures 37 in order that the clearer water under the top of the member 30 can pass on out through said apertures 37. The sides of the member 30 are imperforate between the lower apertures 35 and the upper apertures 37 and are also of stepped formation between said lower and upper apertures, whereby the clothes are agitated by said stepped sides between the 110 lower and upper apertures, and the water can only enter and leave the settling chamber immediately adjacent to the lower edges of the sides and the top of the member 30. The member 30 is hollow to provide a settling chamber therein over the trough 29. This chamber provides a dead water space, in which there is little agitation of the water during the reciprocation of the tub, excepting for the natural tendency of the 115 dirty water to settle to the bottom and flow through the apertures 35 into the settling chamber or dead water space, and for the clearer water at the upper portion of said chamber to pass out through the apertures 120 125 130

37. The dirt thus settles gradually during the washing action from the ends of the tub and the sides 32 of the member 30 to the lower portions 34 of said sides 32, and passes 5 with the water through the apertures 35, and as the dirt is precipitated into the trough 29, the clearer water rises within the member 30 and passes on out through the apertures 37. The member 30 has practically 10 an oscillating motion during the reciprocation of the tub, and the portions 34 swing up and down with little of any motion longitudinally of the tub, whereas the top portion of the member 30 has a small 15 movement longitudinally of the tub, for enhancing the flow of water through the apertures 37.

The ends 31 of the member 30 being inclined will permit said member to be readily 20 lifted off the bottom of the tub for removal, in order to clean said member and tub conveniently, and a drain spout 38 extends from the trough 29 for convenience in draining the water therefrom at intervals. Said 25 spout has a suitable valve 39.

The top portions of the tub formed by the upward and inward extension of the ends are formed with baffles or guards in order to prevent the water from splashing 30 or spilling from the tub during the motion thereof. Thus, the blank from which the ends and bottom of the tub are formed, has its terminal portions extending toward one 35 another and downwardly to define the ends of the mouth or opening of the tub, while the upper portions of the side walls define the sides of the opening or mouth. Each of said terminal portions, as seen in Fig. 1, is bent to provide the curved overhanging 40 portion 40 extending in a direction toward the mouth of the tub, and the metal is then bent back to provide the bead 41 embracing a transverse rod 42 secured to the side walls of the tub to stiffen the structure, and the 45 metal is then doubled or extended under the portion 40, as at 43. From the portion 43, the metal extends inwardly and downwardly, as at 44, and then horizontally to form the seat 45. From the seat 45, the 50 metal extends downwardly at an angle, as at 46, and the end portion of the blank is bent around another transverse rod 47, as at 48, to form a stiff bead. The portions 40 and 43 provide overhanging baffles or 55 guards 49 beyond the seats 45 and opposite ends of the opening or mouth of the tub, for arresting any water that may pass the ends of the cover or lid 50.

The cover 50 is of sheet metal or other 60 suitable material and has flanges 52 to bear on the seats 45 and the inwardly offset side seats 51 of plates 51' at the inner sides of the side walls of the tub. The upper edges of said side walls are beaded, as at 51'', over 65 the upper edges of the plates 51'. The cover

has handles 53. The flanges 52 rest on the seats 45 and 51, and said cover will be below the upper edges of the side walls, whereby the upper portions of said side wall prevent water from splashing or leaking over the 70 sides of the tub, whereas any water passing the ends of the cover and seats 45 will be caught by the baffles or guards 49 and prevented from splashing or spilling over the 75 ends of the tub, such water being thrown back and finding its way into the tub again past the cover. In this way, by having the side walls of the tub extend upwardly above the cover, and by having the baffles or guards 49 beyond the ends of the cover, the 80 annoyance of water splashing or spilling from the tub, during the operation thereof, is eliminated.

The actuating mechanism includes a transverse shaft 54 journaled in the frame 10 below one end of the tub, and having eccentrics 55 thereon at the opposite sides of the tub. Pitmen or links 56 are pivoted to the opposite sides of the tub and have bands or straps 57 embracing the eccentrics 55, in 90 order that the rotation of the shaft 54 will impart a smooth reciprocatory motion to the tub, without a jerking action. Oil troughs 58 are carried by the frame 10 and are so arranged that the eccentrics 55 when 95 rotated will dip in the oil, for lubricating such eccentrics.

In order to rotate the shaft 54, a gear wheel 59 is mounted for rotation thereon at one side of the frame, and meshes with a 100 gear pinion 60. Said gear wheel and pinion are enclosed within a gear case 61 and the pinion 60 is secured on a short transverse shaft 63 journaled in the frame below the tub. A bevel gear wheel 64 is secured on 105 the inner end of the shaft 63 and meshes with a bevel pinion 65 secured to one end of a longitudinal shaft 65' mounted in the frame below the tub, and a pulley wheel 67 secured on said shaft 65' is connected by 110 an endless belt 68 with a pulley wheel 69 on the armature of an electric motor 70 carried by the opposite side of the frame. The power is thus transmitted from the motor 115 to the gear wheel 59, and a clutch is provided for connecting the shaft 54 with said gear wheel.

The clutch for bringing the tub into and out of motion, includes a spool-shaped clutch member 71 slidable on a splined portion 72 of the shaft 54 beyond the gear wheel 59, and the hub of the gear wheel and adjacent end of the clutch member 71 have clutch teeth 73 to engage one another, whereby the clutch member and shaft are compelled to turn with 120 said gear wheel. A clutch shift lever 74 has one end engaged in the groove 74' of the clutch member 71, and said lever is fulcrumed, as at 75, to the gear case 61, whereby 125 the lever can be conveniently swung by hand, 130

for closing and opening the clutch to start and stop the tub at will.

In order to retain the clutch member in either position, a catch pin 76 is slideable in a bore 77 in the portion 72 of the shaft 54, and is projected from said bore by means of a coiled spring 78 within the bore confined behind said pin. The pin has a rounded end to snap into recesses or notches 79 in the clutch member 71. Said pin is cammed out of either notch 79 by the movement of the clutch member, and will snap into the other notch, to retain the clutch member in the corresponding position against accidental movement, but permitting the clutch member to be shifted when slid by the manual pressure on the lever 74. The clutch is also preferably housed within the gear case 61, as seen in Fig. 4.

In operation, after the water, clothes and soap have been put in the tub, and the cover 50 inserted to close the tub, the tub is reciprocated by moving the lever 74 to bring the clutch member 71 into engagement with the gear wheel 59 during the operation of the motor 70. This reciprocation of the tub will throw the water back and forth therein, and the water in impinging against the opposite sides of the member 30 will be deflected upwardly from end to end in the tub, giving the water a motion somewhat in the form of the figure 3. The clothes contacting with and rubbing past the stepped sides 32 of the member 30 will assist in dislodging the dirt from the clothes, owing to the rubbing action, similar to the action of clothes on an ordinary wash board. The water in the settling chamber or dead water space under the member 30 has very little motion, and the dirty water will settle to the bottom and pass through the apertures 35 under the member 30 to the trough 29, while the clearer water under said member at the top will pass out through the apertures 37 assisted by the centrifugal action when the tub is rocked, it being noted that the member 30 has an arcuate motion about a point below said member. A circulation through the member 30 is thus established, with a comparatively slow action, in order that the dirt can settle into the trough 29, and the motion of said member 30 and trough is just sufficient for the precipitation of the dirt into the trough without agitating or stirring up the sediment. The dirty water can be drained out from the trough through the spout 38 at intervals, the tub being stopped by opening the clutch to permit the valve 39 to be opened for the draining of the dirty water from the tub. Said valve is again closed after the dirty water has been drained out, and additional fresh water can be poured into the tub before it is again started in motion by the closing of the clutch.

The upwardly-diverging side walls of the tub permit the cover 50 and also the member 30 to be readily removed from the tub, and this also permits the interior of the tub as well as the member 30 to be cleaned thoroughly and easily.

The actuating mechanism can also be used for the operation of a wringer (not shown). Thus, a vertical shaft 80 is disposed for rotation in a vertical tubular casing 81, and has a bevel gear 82 secured thereto near its lower end meshing with a bevel gear 83 secured to the outer end of the shaft 63. The casing 80 is secured to one end of a cross bar 84 disposed above the tub and supported by braces 85 secured on the sides of the frame 10, and converging upwardly to the bar 84 to which said braces are secured. The wringer mechanism not being a part of this invention is not shown or described, although provision is made for the wringer as just described.

Having thus described the invention, what is claimed as new is:—

1. A washing machine including a reciprocatory tub, and a sheet metal member on the bottom of the tub having inclined converging sides and a top between said sides, said sides having lower small apertures therein immediately adjacent to the lower edges of the sides and also having upper small apertures immediately adjacent to the top, the lower edges of the sides seating on the bottom of the tub, the tub having draining means below said member, and said sides being imperforate between said lower and upper apertures.

2. A washing machine including a reciprocatory tub, and a sheet metal member on the bottom of the tub having inclined converging sides and a top between said sides, said sides having lower small apertures therein immediately adjacent to the lower edges of the sides and also having upper small apertures immediately adjacent to the top, the lower edges of the sides seating on the bottom of the tub, the tub having draining means below said member, said sides being imperforate between said lower and upper apertures and said sides being of stepped formation between said lower and upper apertures.

3. A washing machine including a reciprocatory tub, the bottom of which has a trough, said trough having draining means, and a member disposed on the bottom of the tub for agitating the water and clothes and providing a settling chamber for dirty water thereunder above said trough, said member having means to fit in said trough for holding the member in place.

4. A washing machine including a reciprocatory tub, the bottom of which has a transverse trough, a member disposed on the bottom of the tub having ends to be dis-

posed adjacent to the sides of the tub and sides arranged for the agitation of the water and clothes thereover, said member forming a settling chamber for dirty water
5 thereunder, and portions carried by the ends of said member to fit in said trough for holding said member in place.

In testimony whereof I have signed my name to this specification in the presence of two subscribing witnesses.

ROSS ALEXANDER WORKMAN.
